HAND PUNCH PRESS

Francisco Lago, Staten Island, N. Y.

Application January 20, 1945, Serial No. 573,792

6 Claims. (Cl. 164—96)

This invention relates to new and useful improvements in a hand punch press.

More specifically, the present invention proposes a punch device of the hand operated type characterized by having a pivoted punch holder which can be swung to a position enabling the punch therein to be removed without removing the punch holder.

Still further, it is proposed to provide a punch device of the aforesaid type having an adjustable guide for the reciprocating parts of the device.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side view of a punch device constructed in accordance with this invention.

Fig. 2 is a front view of the device.

Fig. 3 is a rear view of the device.

Fig. 4 is a bottom view of the device.

Fig. 5 is a section on the line 5—5 of Fig. 1.

Fig. 6 is an enlarged foreshortened side view of the device with a side plate removed to show internal parts thereof.

Fig. 7 is a section on the line 7—7 of Fig. 6.

Fig. 8 is a section on the line 8—8 of Fig. 6.

Fig. 9 is a section on the line 9—9 of Fig. 6.

Fig. 10 is a section on the line 10—10 of Fig. 9 showing parts removed and the punch holder in inoperative position to permit removal of the punch.

Figures 11, 12 and 13 are detail views.

The punch device, according to the present invention, is adapted to punch holes in metal, leather, wood and other substances. It is shown devised for hand operation, but it may be power operated if desired. A relatively small punch is shown in the drawings, but, as will later more fully appear, the device is adapted to use various size punches for forming a range of holes.

The punch device comprises a base 10 having a rectangular part 11 and a collar 12. The collar 12 is provided with four set screws 13 which act to removably hold a sleeve 14 in the collar, the sleeve housing a die 15 for coaction with the punch, as will later appear, the hollow center of the sleeve 14 being large enough to receive all the different size punch dies which the device will employ, there being a punch die for each punch used in the device.

Two side plates 16 are secured to the base 10,

5 these plates forming the supporting means for various other of the parts of the device. The plates 16 are secured to the base 10 by bolts 17 and the base is provided with holes 18 for securing the device to a work bench.

A block 19 is secured rigidly between the plates 16, the block being cut out at its top front corner providing a shoulder 20. A guide 21 is supported on the block by means of a flange 22 slidably disposed in the shoulder. This flange is provided with a slot 23 through which extends a bolt 24 securing the flange to the block but permitting movement relative thereto. This block is provided with two threaded orifices 25 perpendicular to the rear face 26 of the guide and adjustment screws 27 are threaded in orifices 25 for adjusting the position of the guide forwardly and rearwardly. The front wall of the block is lined with a wear plate 28. The guide has a vertical groove 29 having two diverging side faces.

A cam member 30 having an orifice 30', is journalled in the side plates at the front of the block 19 and thereabove, by a cam shaft 31 extending through the orifice 30', cam shaft 31 fitting in thickened boss portions 32 of the side walls and being secured therein by washers 33 and screws 34. The cam member 30 has an orifice 35 eccentric to the cam shaft axis 15 and a pin 36 is mounted in this orifice and in turn supports a punch holder 37, wear plates 38 being provided between the punch holder and the side walls. Pin 36 pivotally mounts the punch holder so that it can swing relative to the cam. The punch holder has a recess 39 in its bottom and a punch 40 is secured in this recess by a set screw 41.

The punch holder is best shown in Fig. 11 where it is shown connected to the cam member 30. It has crossing lubricating grooves in its side walls, and a V-shaped rear wall 43 corresponding in shape to the groove face of the guide 21. The punch holder is retained against the guide by a plate 44, best shown in Fig. 12, this plate 44 having transverse horizontal threaded orifices 45 in which are threaded bolts 46 securing plate 44 to the side plates 16. Thus plate 44 forms a front backing plate for the sliding punch holder just as the grooved guide forms a rear backing plate. In practice, to adjust the clearance between the guide and the plate 44, the punch operating handle later to be described, is pulled forward to move the punch holder into the best position for obtaining an adjustment, and then the adjustment screws 27 are employed to move the guide into working fit with the punch holder and the punch holder into working fit with the plate 44.

Plate 44 can be removed easily by removing bolts 46, and then the punch holder can be swung forward, as shown in Fig. 10, to a position permitting the set screw 41 to be loosened, the punch 40 to be removed, and a new punch placed in the punch holder. The punch 40 has a wide base 41 and a narrow punch part 48. Other punches having the same size base but larger or smaller punch parts can thus easily be secured in the same punch holder. The top of the punch holder is formed more or less fork-shaped to receive the cam 30 as is clearly shown in Fig. 9.

An operating handle 49 is rigidly secured between two spaced links 50 by two bolts 51 and 52 and the two links are mounted on the trunnions 31 of the cam 30 and secured thereto against rotation thereon by keys 53. Thus movement of the handle 49 causes corresponding movement of the links and rotation of the cam. The operating handle is adapted to swing from substantially vertical position to substantially horizontal position, as is clearly shown in Fig. 6. In vertical position, the punch is withdrawn from the die and in horizontal position the punch is in the die, this position being the position reached by the punch after the punching operation.

A latch 54 is mounted on bolt 51 for swinging thereon. This latch has a rear bottom catch 55 and a front top catch 56. The front catch 56 coacts with a lever 57 pivotally mounted on the cam 30 and secured to the back of the plates 16 by screws 59. When the handle is in vertical position, the rear catch 55 coacts with the member 58 to hold it in this position and before the handle can be swung forward to move the punch downwardly on its punching stroke, the lever 57 must be moved to release the latch 54 so that the rear catch can be released from the member 58. Latch 54 is formed of two side members 60 connected by an integral front part 61.

Plate 44 is provided with a cut out portion 62 on its rear face at the top to provide clearance permitting the handle to be swung to horizontal position. The rear face of plate 44 including the rear face of the cut out portion is lined with a wear plate 63 secured by a screw 64 threaded in an orifice opening into the cut out portion. A channel 65 is cut through the bottom of the plate 44 and wear plate 63, this channel exposing set screw 41 so that it can be tightened in case it gets loose without removing plate 44.

The operation of the punch device is as follows:

Assuming that first a new punch must be put in the device, the bolts 46 on opposite sides of the plate 44 are removed, the plate 44 is removed and the punch holder 37 is swung forwardly as shown in Fig. 10. The set screw 41 is then loosened and the punch removed and a new punch or a punch of a different size inserted and the set screw 41 tightened. Also, the set screws 13 are loosened and the die 15 removed and a new die suitable for the new punch installed, whereupon the set screws 13 are tightened and the plate 44 put back and secured in place. The screws 27 are then tightened up so that the punch holder is held between the plate 44 and the guide 21 with working clearance. This may be facilitated by moving the handle 49 forwardly to position the punch holder squarely against the guide. The handle 49 is then returned to vertical position and the device is ready to punch a hole, for instance a hole in a sheet of metal.

The sheet of metal is placed on the die, the lever 57 is moved toward the handle 49 releasing the

latch 54, and the handle 49 is pulled forwardly, the rear catch 55 sliding off of the member 58. As handle 49 moves forwardly and downwardly, the cam shaft 31 is rotated in the orifice 39' of cam member 30 moving the member 30 downward and thereby moving the punch holder downwardly and the punch toward the sheet of metal. The handle 49 is long enough to provide proper leverage to force the punch through the sheet of metal. After the hole is punched, the handle is returned to vertical position whereupon the latch automatically springs into place, locking the handle in this vertical position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A punch device comprising a base, side walls extending upwardly from said base, a die supported on said base, a block rigidly secured to said side walls, a guide supported between said side walls having a slotted flange overlying said block, a bolt in said slot securing said guide to said block for movement relative thereto, means carried by said block for moving said guide, a cam member journaled in said side walls over said die, a punch holder pivotally secured to said cam member for sliding movement vertically along said guide, a backing plate backing said punch holder on the side thereof remote from said guide, a punch secured in said punch holder in alignment with said die, and a handle for operating said cam member to move said punch toward and away from said die.

2. A punch device comprising a base, side walls extending upwardly from said base, a die supported on said base, a block rigidly secured to said side walls, a guide supported between said side walls having a slotted flange overlying said block, a bolt in said slot securing said guide to said block for movement relative thereto, means carried by said block for moving said guide, a cam member journaled in said side walls over said die, a punch holder pivotally secured to said cam member for sliding movement vertically along said guide, a backing plate backing said punch holder on the side thereof remote from said guide, a punch secured in said punch holder in alignment with said die, a handle for operating said cam member to move said punch toward and away from said die, and latch means for locking said handle in raised position.

3. A punch device comprising a base, side walls extending upwardly from said base, a die supported on said base, a block rigidly secured to said side walls, a guide supported between said side walls having a slotted flange overlying said block, a bolt in said slot securing said guide to said block for movement relative thereto, means carried by said block for moving said guide, a cam member journaled in said side walls over said die, a punch holder pivotally secured to said cam member for sliding movement vertically along said guide, a removable backing plate backing said punch holder on the side thereof remote from said guide, a punch removably secured in said punch holder in alignment with said die, and a handle for operating said cam member to move said punch toward and away from said die, said

holder being swingable when said backing plate is removed to facilitate removal of said punch from said holder.

4. A punch device comprising a base, side walls extending upwardly from said base, a die supported on said base, a block rigidly secured to said side walls, a guide supported between said side walls having a slotted flange overlying said block, and a V-shaped vertical channel remote from said block, a bolt in said slot securing said guide to said block for movement relative thereto, means carried by said block for moving said guide, a cam member journaled in said side walls over said die, a punch holder pivotally secured to said cam member and having a V-shaped vertical face for sliding movement vertically along said guide channel, a backing plate backing said punch holder on the side thereof remote from said guide, a punch secured in said punch holder in alignment with said die, and a handle for operating said cam member to move said punch toward and away from said die.

5. A punch device comprising a base, side walls extending upwardly from said base, a die supported on said base, a block rigidly secured to said side walls, a guide supported between said side walls having a slotted flange overlying said block, a bolt in said slot securing said guide to said block for movement relative thereto, means carried by said block for moving said guide, a cam member journaled in said side walls over said die, a punch holder pivotally secured to said cam member for sliding movement vertically along said guide, a backing plate backing said punch holder on the side thereof remote from said guide, having a slot in its lower end, a punch in said punch holder in alignment with said die, a set screw securing said punch in said punch holder, said set screw being in alignment with said slot, and a handle for operating said cam member to move said punch toward and away from said die.

6. A punch device comprising a base, side walls extending upwardly from said base, a die supported on said base, a block rigidly secured to said side walls, a guide supported between said side walls having a slotted flange overlying said block, a bolt in said slot securing said guide to said block for movement relative thereto, means carried by said block for moving said guide, a cam member journaled in said side walls over said die, a punch holder pivotally secured to said cam member for sliding movement vertically along said guide, a backing plate backing said punch holder on the side thereof remote from said guide, having a slot in its lower end, a punch in said punch holder in alignment with said die, a set screw securing said punch in said punch holder, said set screw being in alignment with said slot, and a handle for operating said cam member to move said punch toward and away from said die, said punch holder being pressed in working engagement with said backing plate by said adjustable guide.
